US00D893026S

(12) **United States Design Patent** (10) **Patent No.:** **US D893,026 S**
(45) **Date of Patent:** **** Aug. 11, 2020**

(54) **VAGINAL DILATOR**

(71) Applicant: **UNIVERSITY OF CENTRAL
LANCASHIRE**, Preston, Lancashire
(GB)

(72) Inventor: **Peter Leather**, Preston (GB)

(73) Assignee: **UNIVERSITY OF CENTRAL
LANCASHIRE**, Preston, Lancashire
(GB)

(**) Term: **15 Years**

(21) Appl. No.: **29/675,911**

(22) Filed: **Jan. 7, 2019**

Related U.S. Application Data

(62) Division of application No. 29/614,922, filed on Aug. 24, 2017, now Pat. No. Des. 841,806, which is a division of application No. 29/528,416, filed on May 28, 2015, now Pat. No. Des. 798,447.

(57) **CLAIM**

I claim the ornamental design for the vaginal dilator, as shown and described.

DESCRIPTION

FIG. 1 is a left front perspective view of a vaginal dilator showing my new design;

FIG. 2 is a right rear perspective view thereof;

FIG. 3 is a side view thereof, with the opposing side having an identical view;

FIG. 4 is a front view thereof;

FIG. 5 is a rear view thereof;

FIG. 6 is an enlarged top view thereof; and,

FIG. 7 is an enlarged bottom view thereof.

1 Claim, 5 Drawing Sheets
